SEACRAFT

Stephen Turkovich, Pittsburgh, Pa.

Application May 21, 1937, Serial No. 143,990

1 Claim. (Cl. 114—61)

My invention relates to a new type of sea craft, and important objects thereof are to provide a craft of the character described, wherein the main body or superstructure of the ship does 5 rest upon but is spaced from the water, which is supported, sustained and propelled by a plurality of relatively smaller power boats, which embodies a construction tending to camouflage same, which is simple in its construction and 10 arrangement, durable, speedy, light in weight, attractive in appearance, and comparatively economical in its manufacture and operation.

With the foregoing and other objects in view, which will appear as the description proceeds, 15 the invention resides in the novel construction, combination and arrangement of parts herein specifically described and illustrated in the accompanying drawing, but it is to be understood that changes in the form, proportions and details 20 of construction may be resorted to that come within the scope of the claim hereunto appended.

In the drawing wherein like numerals of reference designate corresponding parts throughout the several views:

25 Figure 1 is a side elevational view of a sea craft constructed in accordance with the invention.

Figure 2 is a sectional view on line 2—2, Figure 1.

30 Figures 3 and 4 are rear end views of a power boat and the rudder, respectively.

Referring in detail to the drawing 1 denotes the entire cargo carrying superstructure or main body of the ship. The latter comprises a plurality of large structural ribs 2, which are disposed vertically and parallel in spaced relation to each other, and extend transversely around the ship structure. Each of the structural ribs is preferably an integral structure having a 35 rounded or curved lower portion and a converged or reduced upper portion.

The structural ribs 2 are rigidly secured and fixed in their relative positions by a plurality of superimposed floors or decks 3 joined therewith 45 in any suitable manner and by any suitable type of securing and bracing structures 11. The sides of the main body of the craft, between respective ribs and decks are closed, preferably by suitable heavy, reenforced glass panels 4. It is, of course, 50 evident that the sides of the ship or superstructure may be closed in or covered by steel plates in accordance with the practice now in general use in ship construction.

The interior arrangement and construction of 55 the ship 1 is contingent upon the use for which

the craft is designed or intended to be used. One of the upper decks 3 may be suitably arranged and constructed for the landing and taking off of aeroplanes 5. Further, the ship structure embodies the necessary funnels 6, stacks 7, 5 enclosures, or any other structures facilitating the operation and use of the craft, together with hand or power operated life boats, tanks, rigging, and any other equipment necessary to best meet conditions found in practice.

It will be apparent that the main body or ship 1 may be constructed in any other suitable manner, instead of the preferred form thereof as herein illustrated and described, without departing from the principle or sacrificing any of the 15 advantages of the invention.

The entire main body of the ship or superstructure 1 is carried above and spaced from the water-line, indicated at 8, by a plurality of relatively small power boats 9. Each of the latter is 20 joined with the ship by a suitable supporting structure 10, which also provides a suitable passage giving ready access between the ship and power boat.

The front and rear end power boats 9 are positioned directly beneath the longitudinal center of the ship 1 adjacent to respective ends of the latter. The laterally disposed power boats are positioned laterally outward of the ship to stabilize the entire craft structure, and to eliminate 25 all tendency of the latter to topple over sideways in either direction, even under the most adverse or untoward conditions of the air or sea.

The number and size of the power boats 9 is such that, the latter combinedly will provide sufficient buoyancy to carry, sustain and support the entire ship or superstructure 1 in its spaced 30 relation with the surface of the water in which it is travelling.

Each of the power boats 9 is provided with a 35 pair of propellers 12, which are driven by an independent power unit in the form of an electric motor 13 mounted in each of said power boats. By this arrangement, if one of the power units in one of the boats is impaired for any reason, the power units in the other boats will not be 40 affected thereby and will propel the craft until the disabled boat is repaired.

A suitable dual or two-bladed rudder 14, for 45 steering the craft, is carried by and depends from the ship 1 adjacent to the rear end of the latter, an is preferably electrically operated and controlled.

An electric power plant 15 is preferably centralized and installed in any suitable manner and 50

location in the superstructure or ship 1. The power plant 15 supplies the necessary power for operating and controlling the motors 13 of the power boats 9 and driving the propellers 12, for 5 operating and controlling the rudder 14, and for operating and controlling all other lighting, heating and power devices and apparatus embodied in the craft structure.

It will here be noted that, the principle of my 10 improved type of sea craft may be successfully embodied in any type or class of ocean vessel, regardless of whether the latter be primarily designed and employed for transporting freight or passengers. Even war craft may be economically 15 constructed in accordance with the invention.

The use of glass panels 4 in the sides of the ship 1, in the manner set forth, provides an almost perfect camouflage, making said ship nearly 20 invisible at a distance at sea, and thereby affording such camouflage protection in case the latter is required for any reason, as in case of war and the like. Aside from this camouflage feature 25 of the craft construction, the glass panels 4 admit light throughout the entire ship structure.

The present invention provides a most efficient, improved type of sea craft, which may be economically constructed and operated to facilitate and expedite water transportation.

What I claim is:

In a sea craft, the combination of a large enclosed cargo carrying superstructure, a plurality of comparatively small boats provided with propelling mechanisms joined with said superstructure and being disposed in a pair of longitudinally aligned rows at and laterally outward of 10 respective sides of said superstructure, a pair of comparatively small boats provided with propelling mechanisms joined with said superstructure and being disposed at the longitudinal center of said superstructure adjacent to respective ends of the latter, said small boats supporting, and propelling said superstructure in spaced relation to the surface of the water, and a dual two-bladed rudder mechanism carried by the 15 superstructure disposed intermediate of said pair of rows of laterally disposed small boats and adjacent to the rear boat of said pair of said centrally disposed small boats.

STEPHEN TURKOVICH. 25
